DESIGN FOR A SHOE SOLE OR SIMILAR ARTICLE

Willy Weidner, New York, N. Y.

Application November 15, 1940, Serial No. 96,617

Term of patent 3½ years

To all whom it may concern:

Be it known that I, Willy Weidner, a citizen of the United States of America, residing in New York city, county of New York and State of New York, have invented a new, original, and ornamental Design for a Shoe Sole or Similar Article, of which the following is a specification, reference being had to the accompanying drawing, forming part thereof.

Fig. 1 is a top perspective view of a shoe sole or similar article showing my new design.

Fig. 2 is a bottom perspective view.

Fig. 3 is a side elevational view.

The characteristic feature of my design resides in the combination on the shoe sole disclosed of the contrasting colored tubular stripping around the edge of the shoe sole as shown.

I claim:

The ornamental design for a shoe sole or similar article, as shown and described.

WILLY WEIDNER.
